TOOL SHEATH

Maurice H. Fisher, Douglas County, Colo.

Application July 23, 1953, Serial No. 26,100

Term of patent 14 years

(Cl. D22—6)

To all whom it may concern:

Be it known that I, Maurice H. Fisher, a citizen of the United States, residing in Douglas County, State of Colorado, have invented a new, original, and ornamental Design for a Tool Sheath, of which the following is a specification, reference being had to the accompanying drawing, forming part thereof and in which:

Fig. 1 is a front perspective view of a tool sheath showing my new design;

Fig. 2 is a side elevational view thereof; and

Figs. 3 and 4 are respectively horizontal sectional views thereof taken along the lines 3—3 and 4—4 of Fig. 1.

The dominant features of my new design are shown in solid lines in the drawing. This application is a continuation-in-part of my application Serial No. D.7,545, filed January 28, 1950, and now abandoned.

I claim:

The ornamental design for a tool sheath, as shown and described.

MAURICE H. FISHER.
